ABSTRACT OF THE DISCLOSURE

A rotary safe leak valve having separate inlet and outlet housings disposed with a cylindrical valving member, with an accumulator housing separate from the inlet and outlet housings, the accumulator housing having two separated portions disposed outside of the cylindrical valving member and opposite the inlet housing and outlet housing respectively, and with means to continuously rotate the valving member to first cause flow from the inlet to the accumulator and then cause flow from the accumulator to the outlet.

My invention is concerned with a safe leak valve of the dynamic type wherein a valving member continuously rotates to cause the fluid being valved to sequentially pass from an inlet area to an accumulator area and then from the accumulator area to an outlet area. My invention is an improvement over the copending application of Loren L. Krueger, Ser. No. 566,907, filed July 21, 1966, in that my structure provides a concentric rotary-type safe leak valve.

A rotary safe leak valve constructed in accordance with the teachings of my invention requires dynamic operation such that the failing or stopping of the valve in any position discontinues the flow of fluid through the valve. The rotary valving member first allows fluid to flow from an inlet area to an accumulator area, while blocking flow of fluid from the accumulator area to an outlet area. Thereafter, the fluid which has been accumulated in the accumulator area is allowed to flow to the outlet area, while flow from the inlet area to the accumulator area is blocked. The communication between these three areas is accomplished by means of a seal structure which allows movement of the rotary valve member. The seal structure is constructed and arranged such that any leakage of the fluid, as occasioned by wear and the like, is away from the flow path. Thus, failure of any type will not result in uncontrolled flow of fluid from the inlet area to the outlet area.

FIGURE 1 is a side view, partially broken away, showing the relationship of the inlet area, the outlet area, and the accumulator area to the rotary valving means, and

FIGURE 2 is a cross-section view of the structure of FIGURE 1, taken along line 2—2 thereof wherein the structure is not broken away.

Referring to FIGURE 1, reference numeral 10 designates an inlet conduit which is adapted to be connected to a source of fluid under pressure, in this case a compressible fluid such as gas to be used with a fuel burner, reference numeral 11 indicates an outlet conduit which is adapted to be connected to a utilization means, for example, a burner.

2

Conduit 10 is connected to an inlet area 12 whereas conduit 11 is connected to an outlet area 13. Areas 12 and 13 are defined by cup-like structures having terminating rectangular flanges 14 and 15 respectively. Flanges 14 and 15 are formed with rectangular recesses receiving O-ring seal structures 16 and 17 respectively. Seals 16 and 17 cooperate with rotary valving member 18 which is rotatable about a central axis upon energization of motor 19. Valving member 18 is provided with three-spaced openings, 20, 21, and 22 as best seen in FIGURE 2.

Reference numeral 25 identifies the general structure of an accumulator area, the accumulator including a donut-shaped housing 26. Accumulator area 25 includes internal base-like areas 40 and 41, which are adapted to connect the accumulator to the inlet area 12 and the outlet area 13 respectively. Each of the base-like portions 40 and 41 terminates at a rectangular flange 27 and 28, respectively. Flanges 27 and 28 are formed with rectangular recesses receiving O-ring seal structures 30 and 56 respectively.

The rotary safe leak valve of my invention is shown in FIGURE 1 with rotary valving member 18 in position such that inlet area 12 communicates with portion 40 of the accumulator 25. Thus, fluid under pressure can flow into accumulator 25. At the same time, as can be seen in FIGURE 2, a solid portion of valving member 18 blocks communication between accumulator 25 and outlet area 13. As rotation of valving member 18 continues, opening 22 in the valving member moves to a position wherein the accumulator area communicates with outlet area 13 and the accumulated fluid flows to the outlet conduit 11. At that same time, valving member 18 has moved into position to block communication from the inlet area to the accumulator area.

If it is desired to valve a non-compressible fluid, a bellows-type chamber can be incorporated as part of the accumulator area.

The area designated by reference numerals 60, 61, and 62 of FIGURE 2, are exposed to the ambient atmosphere surrounding the valve. Any leakage of fluid past the various sealing means is to the areas 60—62 and no leakage occurs from inlet area 12 to outlet area 13. The structure of my invention provides a rotary valving member wherein dynamic rotation of the valving member is necessary for continuous flow of fluid from inlet conduit 10 to outlet conduit 11. Should the valving member stop in any position, the communication between these conduits is interrupted. If a leak results, all leak paths are away from the flow path and uncontrolled flow between conduits 10 and 11 does not result.

I claim as my invention:

1. A safe leak valve of the type having means refining a flow path including an inlet area, an accumulator area, and an outlet area, the improvement comprising:

a rotary valving member adapted to continuously rotate and including flow control means to sequentially allow flow between said inlet area and said accumulator area while blocking flow between said accumulator area and said outlet area, and to then allow flow between said accumulator area and said outlet area while blocking flow between said inlet area and said accumulator area,

means operably connected to said valving member for continuously rotating said valving member,

and a plurality of sealing means; each one of which cooperates with only one of said areas and with said valving member, such that all leakage through said sealing means is away from said flow path.

2. A valve as defined in claim 1 wherein said inlet area, said accumulator area, and said outlet area have structurally separated flange areas, each flange cooperating with said valving member through one of said plurality of sealing means, such that leakage through said sealing means is away from said flow path.

3. A valve as defined in claim 1 wherein said valving member is in the form of a hollow cylinder which is rotatable about an axis; wherein said inlet and outlet areas are defined by a pair of separated housings disposed within said cylinder, each of said housing including a 15 separate flange which engages the inside surface of said cylinder; and wherein said accumulator area includes two

portions disposed outside of said cylinder and opposite said inlet area housing and outlet area housing respectively, each of said two portions having a flange which engages the outside surface of said cylinder.
